UNITED STATES PATENT OFFICE

2,218,603

RAILWAY CROSSING

Earnshaw Cook, Sterlington, N. Y., and Albert F. Huber, Chicago, and James R. Hewitt, Jr., Chicago Heights, Ill., assignors to The American Brake Shoe and Foundry Company, New York, N. Y., a corporation of Delaware

Application May 22, 1939, Serial No. 274,878

19 Claims. (Cl. 246—464)

This invention relates to railway crossings of the box type, and method of producing the same, in which the footings, the wall members upstanding from said footings, and the horizontal web 5 portion bridging the spaces between the wall members and providing intersecting flangeways and tread surfaces are all formed in one integral casting designed appropriately for optimum foundry practice and uniform heat treatment that 10 is resorted to for developing a desired structure in the metal, for instance, when manganese steel is used, and in which it is also desirable to work-harden the metal of the wheel receiving surfaces at the corners of intersection.

15 One object of the invention is to provide a design of railway crossing which, while leaving the body of the crossing adequately sustained from an underlying base plate, will have its flangeways and wheel treads in the immediate vicinity of the 20 crossing point, free from solid support upon the bed but with vertical support in use at points radially removed from the point of intersection, and at the same time leaving the crossing free for work-hardening of its corner elements under 25 pressure. To this end, such service support as is provided for the bridging web that carries the flangeways and tread surfaces is made removable in order to expose substantially the entire surface directly beneath the tread corners that are to be 30 work-hardened for the introduction of an anvil that will absorb the work-hardening pressure without transmission of strain to the box-like structure; such anvil being removable and the service support in the vicinity of the crossing 35 center being replaceable at will. Another important condition attained by having a removable service support (preferably a grid) as well as a removable anvil in a crossing of this kind, is avoidance of any over-proportioning in thickness 40 of the crossing structure, thereby permitting uniform heat treatment of the crossing, as well as to prevent internal discontinuities normally resulting from the transition of molten metal to solid state, as for example, when the crossing is made 45 of 10-14% manganese steel.

The invention further embodies in its scope the provision of a separate and replaceable grid of such a construction that the same may be used as an anvil adapted to be positioned in supporting 50 relation to the bridging web of the crossing to support the same at the flangeways during the work-hardening of the pads and which may be secured in said supporting relation to said flangeways to provide the completed assembly after 55 the work-hardening has been performed.

As a still further object of the present invention, the same comprehends a structure for the separable and replaceable grid which provides suitable metal sections amenable to proper heat treatment and to prevent internal discontinuities 5 normally resulting in foundry practice from the transition of molten metal to the solid state.

Still a further object within the purview of the present invention is to provide a separable grid which, in its cooperative relation with the flangeways of the crossing, provides substantially uniform extended bearing relation for the flangeways outwardly from their intersection whereby the body portion of the crossing member is of double arched construction, which in effect 15 eliminates the notched beam structure thereof due to the formation of the flangeways therein.

Another object of the invention is to insure successful foundry practice at points in the box-like structure adjacent to lines bisecting the angles 20 between the branches of the crossing through which it is united to track rails, and particularly successful casting of angles of different amplitude between said branches which require variations 25 in the supply of molten metal. To this end, another feature of the invention consists in providing risers at middle points in the vertical walls of the crossing corresponding to the aforesaid bisecting lines.

Other objects have to do with structural details 30 incident to foundry practice and resultant structure constituting features of identification of the invention which will be hereinafter more fully referred to.

Other objects, features, capabilities and advantages are comprehended by the invention, as will later appear and as are inherently possessed thereby.

Referring to the drawings:

Figures 1 to 4, inclusive, are plan views of body 40 portions of crossing structures embodying the several features of the present invention and made for effecting crossings at different angles of intersection;

Figure 5 is a section through a crossing in the vertical plane of intersection and showing the anvil used for condensing pads of metal at the crossing corners;

Figure 6 is a perspective view of a crossing including in its design, metal pads on the tread corners intended to be pressed into coincidence with the upper plane of the treads for the purpose of improving the wearing qualities of the crossing;

Figure 7 is a view of a crossing and in associa- 55

tion therewith the tool used for developing the work-hardening of the treads;

Figure 8 is a perspective view of a crossing such as shown in Figure 6 or Figure 7 in inverted position, with the service support of the bridging web removed, the heads employed for insuring adequate metal at crucial points in the casting being indicated in dotted lines;

Figure 9 is a perspective view of the service support of the bridging web in the vicinity of the crossing center;

Figure 10 is a sectional view of a crossing in its mold, the section being taken in the vertical plane of two heads located on opposite sides of the crossing center and in a plane that bisects the angle between two of the branches that connect the crossing with the track rails;

Figure 11 is a plan view of a crossing of given angularity, showing in dotted lines vertical supporting walls extending transversely to side walls of the box-like structure and integrally uniting portions of the casting which provide the flangeways of the crossing as well as the grid which affords vertical support of the portion of the bridging web in the vicinity of the crossing section;

Figure 12 is a vertical section in a plane indicated by the line 12x—12x in Figure 11;

Figure 13 is a vertical section in a plane indicated by the line 13x—13x in Figure 11;

Figure 14 is a view similar to Figure 11, illustrating by dotted lines the anvil used for rendering service support to the bridging web, this view also showing depressible pads on the crossing corners;

Figure 15 is a vertical sectional view showing the application of an anvil appropriate to the pad-depressing treatment of the crossing shown in Figure 14;

Figure 16 is a view in perspective of an alternative construction for a crossing made in accordance with the present invention, the same being shown in inverted position;

Figure 17 is a view in perspective of the crossing of Figure 16 disclosing a separate and replaceable grid disposed in and connected to the same in operative position; and

Figure 18 is a view in perspective of the grid used in the assembly of Figure 17 of the drawings.

The present application is a continuation-in-part of application Serial No. 214,474, filed June 18, 1938.

Referring to Figures 1 to 7, A represents a body portion and B four crossing branches adapted to connect said body portion with rails of a track in which the crossing is used. C represents flangeways, and D crossing corners developed by said flangeways. Corners D, in Figures 1 to 6, inclusive, are formed with pads E, F and G which, when compressed into coincidence with the tread plane of the crossing, lend to the metal of said corners a structural character that improves the wearing quality of the crossing. H, in Figure 5, represents an anvil conforming to

the under surface of the bridging web of the crossing and projecting below the plane of the base upon which the crossing rests in order to absorb all of the pressure imposed upon the pads E, F and G in developing work-hardening of the crossing corners as described. Anvil H has reentrant portions that admit the ribs C' in which the flangeways C are formed, and these reentrant portions adapt the anvil to sustain the ribs C' against lateral distortion under the high order of pressure imposed in leveling the

pads. The anvil H completely relieves the upstanding walls I of the box-like body of the crossing during the work-hardening of the crossing at the pads and the same is removed and replaced by the grid M, as will hereinafter more fully appear.

In Figure 7, the crossing corners D are smooth or without pads for work-hardening in improving the structure of the treads of the crossing. This may mean either that the pads were omitted as not being necessary in the particular instance, or that such pads have already responded to pressure imposed through the tool K.

The walls I extend diagonally from two adjacent branches B of the crossing structure. Obviously, the mass of metal required to construct the portion of the crossing between two branches B varies according to the characteristic angle of the crossing.

In order to insure ample metal in each diagonal portion, heads L are located at such diagonal portions and will be variously proportioned as indicated in dotted lines in Figure 8, where the characteristic angle of the crossing employs a wide angle on one bisecting line of a crossing and a relatively smaller angle on the other bisecting line of the crossing. As may also be seen in Figure 10, the heads L (shown in full lines, in section) and the head L' (shown in dotted lines) are of different capacity and effect a substantially uniform feed of molten metal in all cases by reason of the relation of their feeding capacity to the volume of metal demanded.

M, in Figure 9, is a grid that affords the service support for the bridging web of the crossing. This consists of spider arms N adapted to enter spotting recesses O (Figure 8) that position the grid until it can be permanently welded into place. The grid is inverted in position in Figure 9. It carries an upstanding step P through which it sustains the bridging wall of the crossing through the medium of the ribs C' which are the portions of the crossing that rest upon said step. Thus the grid is given a Z-shaped section, one portion of which provides a frame M and the other portion a flange or step P, while the projections N lend to the grid the form of a spider which facilitates its mounting in the upstanding walls of the box-like structure. The vertical dimension of the grid M, including the step P, is precisely equal to the distance between the horizontal plane of the under faces of the ribs C' and the plane of the under faces of the upstanding walls I, so that when the crossing stands upon a suitable bed, preferably a plate of substantial thickness, for instance, about $\frac{1}{8}$ inch, the bridging web will be in proper support. The portions of the ribs C' that seat upon the step P of the grid M are somewhat back from the crossing point X, with the result that those portions of the ribs C' lying at the crossing point X are free of immediate support and therefore capable of exercising some resiliency under the load of car wheels.

Figures 11 to 13 inclusive and 14 and 15 show additional illustrative embodiments of modified construction embodying the invention and incorporating elements of similar construction to those shown in the above described figures. Accordingly, similar reference characters have been used and said description of Figures 1 to 10 inclusive equally applies to these figures.

The modified grid crossing construction exemplified in Figures 16 and 17 conforms substantially to the previously described embodi-

ments and similarly includes a body portion A and four crossing branches B adapted to connect the said body portion with rails and a track with which the crossing is used. The flangeways

5 C are provided in this crossing member and intersect at crossing corners as at D in the previously described embodiments, which corners D may be formed with pads, such as E, F and G, all as hereinbefore described. The said walls 10 of the crossing branches B of the present embodiment are reinforced by way of webs 10 and 12 and the said webs intersect as at 14 to provide channel-shaped members at the points where the risers or heads are located for feeding 15 the molten metal into the mold forming the same.

The present embodiment embraces a grid 16 adapted to have cooperative bearing relation with the ribs C' in which the flangeways C are formed to provide a support for the arched bridging web 20 of the crossing when the same is in operative position, it being further contemplated that the grid serve also as an anvil to support the said ribs C' during the work-hardening process constituted by pressure imposed in leveling the pads 25 E, F and G.

In order to provide a grid which will serve in this dual capacity and will properly support the ribs of the flangeways when the device is subjected to wheel loads, the said grid 16 is formed 30 with radially disposed arms 18, 20, 22 and 24, each of which is provided with a recess, such as 26, terminating in spaced relation to one another adjacent the central portion of the grid member to provide the hub 28 of solid construction. The said recesses 26 are formed to provide 35 opposed upstanding walls, such as 30 and 32, and an integrally formed bridging web 34 for each of the arms. The base portion of this grid is formed as by means of intersecting webs 36 40 and 38 laterally extending from the upstanding webs 30 and 32 between the adjacent arms, thus providing extended bearing surfaces for supporting the grid in operative position.

The grid 16 has an extended bearing area defined by the outline of the radially extending arms and the hub whereby the grid is adapted to have extended bearing engagement with the bridging web of the crossing immediately below the intersection of the said flangeways and for 50 a substantial distance outwardly therefrom along the said ribs, it being understood, of course, that this extended and uniform bearing relation of the grid with this bridging web is effected through the plane surfaces of the under side of the ribs 55 which engage the grid.

In order to position the grid in its assembled relation to the crossing, weld joints 40 are provided between the intersections 14 and webs 36 of the grid, these welds being flush with the bottom surface of the grid and the surfaces formed by the intersections 14.

By providing a structure of the type disclosed in Figures 16 to 18 inclusive, the grid which is used in the final assembly as a support for the bridging web of the crossing can be effectively used as an anvil during the process of work-hardening the pads which may be formed on the upper surface of the crossing adjacent the intermediate section of the flangeways. Furthermore, the separable grid provides a structure having all of the attributes of the herein described embodiments insofar as foundry practice is concerned, and the welds 40 are such that the grid may be replaced 70 at any time by cutting these welds and inserting

a new grid in place of the one formerly connected to the crossing member.

While we have herein described and upon the drawings shown illustrative embodiments of the invention, it is to be understood that the invention is not limited thereto but may comprehend other constructions, arrangements of parts, details and features without departing from the spirit of the invention.

We claim:

1. A railway crossing structure of substantially the character described, comprising a box-like structure formed with a body and a plurality of crossing branches having upstanding portions and a top portion in the form of a bridging web 15 integral with the said upstanding portions and connecting the same, said upstanding and bridging portions being so constructed and arranged as to provide substantially uniform sections amenable to proper heat treatment and to prevent internal discontinuities normally resulting from the transition of molten metal to solid state, and the bridging portion being formed with flangeways and tread surfaces, and the portions in which the flangeways are formed being developed as downwardly presented ribs terminating short of the plane of the base of the upstanding portion, said crossing being provided with a separately formed load-sustaining grid disposed within said body upon which the flangeway ribs 30 are seated, and the thickness of said grid being such that its under face lies in the plane of the surfaces from which the upstanding members rise.

2. In a railway crossing structure of substantially the character described, a box-like structure formed with a body and a plurality of crossing branches including upstanding walls and a bridging web portion connecting the tops of adjacent walls, said web portion providing flangeways and wheel receiving surfaces, a supporting grid disposed within said body presenting seats for the bridging web portion beneath a portion of the flangeways, and seating recesses in the upstanding walls of the crossing receiving and positioning the grid.

3. A railway crossing structure as described in claim 2, in which the grid comprises a frame portion extending inwardly from the portion that is received by the upstanding walls, and a step 50 extending inwardly and upwardly from said frame portion and providing the seats for the web portion.

4. In a railway crossing structure of the character described comprising a box-like structure 55 including upstanding walls, a separately formed supporting grid of Z-section, and means for connecting said grid to the upstanding walls of the crossing.

5. A railway crossing structure as described in claim 1, in which the said grid comprises upstanding webs integrally connected with a bridging web.

6. A railway crossing structure as described in claim 1, in which the said grid is formed with 65 radially extending arms having bearing relation throughout their length with said flangeway ribs.

7. A railway crossing structure as described in claim 1, in which the said grid is formed with 70 radially extending arms provided with bridging webs having bearing relation throughout their length with the said flangeway ribs.

8. A railway crossing structure as described in claim 1, in which the faces of the said flangeway ribs are substantially in a plane parallel to the 75

plane of the base adjacent the intersection thereof and the said grid is formed with radially extending arms having the upper surface thereof substantially in a plane and having substantially 5 uniform bearing relation with the said faces of the flangeway ribs.

9. A railway crossing structure as described in claim 1, in which the faces of the said flangeway ribs are substantially in a plane parallel to the 10 plane of the base adjacent the intersection thereof and the said grid is formed with radially extending arms provided with bridging webs having the upper surface thereof substantially in a plane and having substantially uniform bearing 15 relation with the said faces of the flangeway ribs.

10. In a railway crossing structure of substantially the character described, a box-like structure formed with a body and a plurality of crossing branches including upstanding walls 20 and a bridging web portion, said web portion providing intersecting flangeways and wheel receiving surfaces, and a supporting grid having radially extending arms presenting seats for the bridging web portion beneath a portion of the 25 flangeways.

11. In a railway crossing structure of substantially the character described, a box-like structure formed with a body and a plurality of crossing branches including upstanding walls and 30 a bridging web portion connecting the tops of adjacent walls, said web portion providing intersecting flangeways and wheel receiving surfaces, and a supporting grid having radially extending arms provided with bridging webs presenting 35 seats for the bridging web portion beneath a portion of the flangeways.

12. In a railway crossing structure of substantially the character described, a box-like structure formed with a body and a plurality of 40 crossing branches including upstanding walls and a bridging web portion connecting the tops of adjacent walls, said web portion providing intersecting flangeways and wheel receiving surfaces, and a supporting grid, said supporting grid 45 being provided with a hub presenting a seat for the bridging web portion beneath the flangeways adjacent their intersection and radially extending arms provided with recesses terminating at the hub and presenting seats for the bridging 50 web portion beneath a portion of the flangeways outwardly of their intersection.

13. In a railway crossing structure of substantially the character described, a box-like structure formed with a body and a plurality of 55 crossing branches including upstanding walls and a bridging web portion connecting the tops of adjacent walls, said web portion providing intersecting flangeways and wheel receiving surfaces, said bridging web portion beneath the 60 flangeways presenting flat grid engaging surfaces, and a supporting grid having radially extending arms presenting flat surfaces engaging said grid engaging surfaces beneath a portion of said flangeways.

14. In a railway crossing structure of substantially the character described, a box-like structure formed with a body and a plurality of crossing branches including upstanding walls and a bridging web portion connecting the tops of adjacent walls, said web portion providing intersecting flangeways and wheel receiving surfaces, a supporting grid having radially extending arms 10 presenting seats for the bridging web portion beneath a portion of the flangeways, and a weld joint between said radially extending arms and the intersection of said upstanding walls for connecting said grid to said crossing. 15

15. A cast metal grid of integral construction for a railway crossing having intersecting flangeways, comprising a central body portion and radially extending arms each provided with upstanding webs connected adjacent their top edge with a bridging web for support of the flangeways of said crossing. 20

16. A cast metal grid of integral construction for a railway crossing having intersecting flangeways, comprising a hub and radially extending arms, each of said arms comprising upstanding webs integrally formed with a bridging web for 25 support of the flangeways of said crossing.

17. A cast metal grid of integral construction for a railway crossing having intersecting flangeways, comprising a central body portion and radially extending arms each provided with 30 spaced walls connected together by a connecting wall to provide recesses on the underside of said grid which terminate in spaced relation at the central body whereby a hub is formed therebetween, said hub and connecting walls being provided for support of the flangeways of said crossing. 35

18. The process of producing a railway crossing, comprising the steps of fashioning said crossing of box-like structure wherein the same includes a bridging web portion having the upper surface thereof formed with pads, positioning a grid in supporting relation to said bridging web, work-hardening said pads while said grid serves as an anvil in supporting relation to said web, and securing said grid in said supporting position with respect to said web to complete the assembly. 40 45

19. In a process of producing a railway crossing characterized by being of box-like construction embracing therein a separately formed supporting grid connected thereto, the steps of fashioning said crossing of box-like structure wherein the same includes a bridging web portion having the upper surface thereof formed 55 with pads, positioning said grid in supporting relation to said bridging web, and work-hardening said pads with said grid serving as an anvil in supporting relation to said web. 60
